UNITED STATES PATENT OFFICE.

CHARLES W. DARROW, OF GLENWOOD SPRINGS, COLORADO.

FLUSHING DEVICE.

1,107,911.

Specification of Letters Patent.

Patented Aug. 18, 1914.

Application filed April 16, 1913. Serial No. 761,638.

To all whom it may concern:

Be it known that I, CHARLES W. DARROW, of Glenwood Springs, in the county of Garfield and State of Colorado, have invented 5 certain new and useful Improvements in Flushing Devices; and I do hereby declare the following to be a full, clear, and exact description of the invention, such as will enable others skilled in the art to which it app- 10 pertains to make and use the same.

The primary object of this invention is to produce an extremely simple and inexpensive flushing device, which will be free from noise, capable of being started and stopped 15 without shock or wire drawing, and which will be composed of but few parts.

In the accompanying drawings, Figure 1 is a longitudinal sectional view. Fig. 2 is an end view, partly in section, showing the 20 control valve in the position it occupies when the main valve is seated. Fig. 3 is a view somewhat similar to Fig. 2, showing the control valve moved to allow the main valve to be unseated.

25 Referring to the drawings, 1 designates a casing; 2 the inlet; 3 the outlet; and 4 a by-pass leading from the inlet to the pressure chamber of the casing. Communication between inlet 2 and outlet 3 is controlled by a 30 main valve 5, which is shown as having a cylindrical body portion fitting within the pressure chamber, and as having a tapered portion 6 which, when it engages its two seats, will cut off the flow of water, said 35 tapered portion 6 terminating in a lug 7, which I have shown as located centrally of the inlet opening. When the valve is opened the lower portion of this lug is within the 40 plane of the upper end of the inlet opening so that the outflow will be restricted, thus causing a damming of the water at this point and a consequent greater force or pressure through the by-pass to the upper side of the 45 valve, thus insuring closing of the valve against the inlet pressure. This valve 5 is free to turn on its axis while moving longitudinally toward and away from its seats.

50 The entrance of the water through by-pass 4 into the pressure chamber is controlled by a swinging valve 8, which is pivoted at the axis of casing 1 on a stud 9 extended through end cap 10, an operating handle 12 being secured to said stud. I have 55 shown packing 13 surrounding the inner end of the stud and bearing against the face of

cap 10. The valve 8 is preferably in the form of a sector, and is provided with an arcual slot 14 so as to form a spring arm carrying valve face 15, which is designed to cut off the entrance of water from the by-pass to the pressure chamber. This valve 8 has a radial face which carries a disk 16 of any suitable material for closing the outlet from the pressure chamber when the by-pass is open, and for opening such outlet when the by-pass is closed. I have shown the outlet from the water chamber as consisting of a pipe 17, held in place by a plug and which may be connected to the bowl.

As shown in Fig. 2, when valve 8 is moved to uncover the by-pass, the outlet through pipe 17 is closed by the radial portion of the valve. When the latter is in this position pressure will build up and effect the seating of the main valve against the incoming water. When the control valve is moved into the position shown in Fig. 3, the by-pass is cut off, and the pressure is relieved by uncovering pipe 17, permitting the main valve to be automatically unseated. Normally, the 70 operating handle 12 occupies a horizontal position, as indicated in Fig. 2. When raised to permit the operation of the flusher, it will promptly return to its normal position by gravity, and in so doing will move the control valve to close the outlet from the pressure chamber, and open the inlet thereto 75 through the by-pass. Within the by-pass 4 I locate a cock 20 by adjusting which the quantity of water allowed to flow through 80 the by-pass for seating the main valve may be controlled, and by reason thereof also the time required for the main valve to return to 85 its seat.

The advantages of my invention will be 90 apparent to those skilled in the art. It will be noted that in my present flushing device the use of springs is unnecessary; that the device is composed of comparatively few 95 parts, and hence not liable to readily get out of order; it will close without jar or shock; is noiseless in operation; and the main valve being free to turn on its own axis will wear longer than one moving on fixed lines, and having a double seat the wear is reduced one-half of what it would be with but a single 100 seat.

I claim as my invention:

1. A flushing device comprising a casing having an inlet, an outlet, a pressure cham- 110

- 2
- ber, and a by-pass connecting said pressure chamber with the inlet side of the casing, a main valve fitted in said chamber and designed to cut off communication between the inlet and outlet, said valve having a centrally extended lug which is designed to fit in said inlet to restrict the outflow when the valve is opened, said pressure chamber having a relief outlet on the same plane as, but 10 away from the entrance of, said by-pass into said pressure chamber, a disk-like rotary valve having port controlling faces in parallelism with the axis of said valve for normally closing the outlet of the pressure chamber and opening communication between the latter and said by-pass, and an operating handle for rotating said valve to uncover said latter outlet and close communication with said by-pass.
- 20 2. A flushing device comprising a casing having an inlet, an outlet, a pressure chamber, and a by-pass connecting said pressure chamber with the inlet side of the casing, a main valve fitted in said chamber, and designed to cut off communication between the inlet and outlet, said pressure chamber having a relief outlet, a rotary valve having a spring arm for closing said by-pass, and also having a radial portion for closing the outlet 25 from the pressure chamber, which outlet is at right angles to the pressure chamber, and

an operating handle for moving said control valve.

3. A flushing device comprising a casing having an inlet, an outlet, a pressure chamber, and a by-pass connecting said pressure chamber with the inlet side of the casing, said pressure chamber having an outlet, a main valve of cylindrical formation capable of moving longitudinally in said pressure chamber and having a reduced portion, said valve being capable of turning on its axis, a control valve in the form of a sector having two port-controlling faces, one face controlling said by-pass, and the other the 40 outlet from the pressure chamber.

4. In a flushing device having a pressure chamber, a port leading into said pressure chamber, and an outlet pipe leading from the pressure chamber at right angles thereto, a valve in the form of a sector having a spring arm, the end of which is designed to extend over said by-pass, said valve also having a radial face for closing said outlet pipe. 50

In testimony whereof, I have signed this specification in the presence of two subscribing witnesses.

CHARLES W. DARROW.
